ADSORPTION METHOD FOR SEPARATING METAL CATIONS

Joseph X. Khym, Santa Fe, N. Mex., assignor to the United States of America as represented by the United States Atomic Energy Commission

Application May 9, 1946, Serial No. 668,636

23 Claims. (Cl. 23—23)

This invention relates to the separation of substances by means of chromatographic adsorption, and in particular to a method of separating cations contained in a solution which involves adsorbing the cations upon an adsorbent and selectively eluting the desired cations from the adsorbent.

As described herein, the isotope of element 94, having a mass of 239, is referred to as $^{94}\text{Pu}^{239}$ and is also called plutonium, symbol Pu. In addition, the isotope of element 93 having a mass of 239 is referred to as $^{93}\text{Np}^{239}$ and is called neptunium, symbol Np. Furthermore, the term "values" or its equivalent when employed herein with reference to an element is intended to embrace the element and compounds thereof. For example, the term "columbium values" is intended to include columbium as well as compounds thereof. The term "activity" or its equivalent when employed herein with reference to a radioactive element is intended to include the radioactive element and compounds thereof. For example, the term "columbium activity" as employed herein is intended to include radioactive columbium as well as compounds thereof.

Naturally occurring uranium contains a major portion of $^{92}\text{U}^{238}$, a minor portion of $^{92}\text{U}^{235}$ and small amounts of other substances such as UX_1 and UX_2 . When a mass of such uranium is subjected to neutron irradiation, particularly with neutrons of resonance or thermal energies, $^{92}\text{U}^{238}$ by capture of a neutron becomes $^{92}\text{U}^{239}$ which has a half life of about twenty-three minutes and by beta decay becomes $^{93}\text{Np}^{239}$. The $^{93}\text{Np}^{239}$ has a half life of about 2.3 days and by beta decay becomes $^{94}\text{Pu}^{239}$. Thus, neutron irradiated uranium contains both $^{93}\text{Np}^{239}$ and $^{94}\text{Pu}^{239}$, but by storing irradiated uranium for a suitable period of time, the $^{93}\text{Np}^{239}$ is converted almost entirely to $^{94}\text{Pu}^{239}$.

In addition to the above mentioned reaction, the reaction of neutrons with fissionable nuclei such as the nucleus of $^{92}\text{U}^{235}$ results in the production of a large number of radioactive fission products. For example, when an atom of $^{92}\text{U}^{235}$ undergoes fission, two fragments are formed. These fragments vary sufficiently in their masses and hence their atomic numbers to give some 34 elements, all of which initiate further reaction chains with the emission of radiations. These chains are the source of all of the radioactivity that renders isolation of any one of the products of irradiation of uranium so difficult. The radiations include: (1) beta or high speed negative electrons with variable energy contents, and therefore, different velocities, (2) soft gamma, or electro-magnetic radiation similar to X-rays but with a shorter wave length and moderately higher energy content, (3) hard gamma similar to the soft type except that it has a shorter wave length and higher energy content, and (4) neutrons.

In general, the stability of an atom depends on the ratio of protons to neutrons in the nucleus and certain ratios, therefore, result in an excess energy content

that must be emitted as radiation before a stable end product is formed. While most naturally occurring isotopes are stable and therefore not radioactive, those resulting from fission have proton-neutron ratios such as to cause internal instability. As a result, they tend to stabilize and in the process emit their excess energies in one of five general ways.

In the first place, an atom may emit a beta particle from the nucleus where the only possible source of a negative electron is from a neutron which gives both a positive and negative charge. The loss of the negative charge converts the neutron to a proton and there is a gain of one in atomic number and hence a transmutation to the next higher element. Such a change, of course, alters the proton to neutron ratio and may result in a stable atom, although this is not necessarily true.

In the second place, a beta particle of lower energy content may be emitted, thus forming the next higher element while still leaving the nucleus with too great an energy content to be stable. The first beta particle may then be followed by another one to form the second higher element in the atomic series which again may or may not be stable.

Thirdly, a beta particle of intermediate energy may be emitted to form an unstable isotope of the next higher element which, due to its excess energy, may give off a gamma ray rather than a beta particle. This process also may result in either a stable or an unstable atom.

Fourthly, the beta-decay of a fission product may leave the nucleus in a state of excitation higher than the binding energy of a neutron in that nucleus. The neutron is then immediately emitted, and the rate of decay of the neutron-emitting activity observed is just that of the preceding beta activity.

Finally, an unstable atom may emit a gamma ray which strikes an electron in one of the inner shells of electrons and ejects it in such a condition that it has some of the properties of the nuclear beta particle. Since the electron, which in this case is known as photo-electron, does not originate in the nucleus, there is no change in the atomic number and the process, like that involved in the emission of a gamma ray, is known as internal conversion.

With the exception of elements 43 and 61, the fission products formed by the above discussed reaction are all well known elements with normal chemical properties, the only point of difference between them and the natural element being that they are composed of unstable isotopes. As brought out above, due to their internal instability they either undergo transmutation to other elements or stabilize themselves internally by the emission of one or more of the previously-mentioned radiations. Consequently, stabilization may involve no change in atomic number or a change of several units. The average length of the fission chains, that is the number of transmutations, is about 3.2 but some may be as long as 6. In general, a chain reaction has emitted a total of 25 to 30 m. e. v. as radiation by the time it is complete.

The fission of $^{92}\text{U}^{235}$ yields two general types of elements, namely heavy and light. The light fission products possess atomic numbers between 30 and 46 and include radioactive zinc, gallium, germanium, arsenic, selenium, bromine, krypton, rubidium, strontium, yttrium, zirconium, columbium, molybdenum, 43, ruthenium, rhodium, and palladium.

The heavy fission products resulting from neutron irradiation of $^{92}\text{U}^{235}$ possess atomic numbers ranging from 47 to 63 and include radioactive silver, cadmium, indium, tin, antimony, tellurium, iodine, xenon, cesium, barium,

lanthanum, cerium, praseodymium, neodymium, 61, samarium and europium.

Generally speaking, the irradiation of uranium is conducted under such conditions as result in the combined amount of neptunium and plutonium being equal to approximately 0.02% by weight of the uranium mass. The concentration of the fission products in neutron irradiated uranium is approximately the same as that of the total of the plutonium and neptunium. However, since many of the fission products are radioactive, they change to other elements at certain fixed rates which are characteristic of each fission product. In other words, they have fixed decay rates. Plutonium, on the other hand, is relatively stable, and since the fission products have varying decay rates, the concentration of the initially formed radioactive fission products with respect to plutonium changes substantially during the course of the reaction and particularly during the storage period which is generally employed after the neutron irradiated uranium has been removed from the reaction zone.

The quantities of the various individual radioactive fission products present in neutron irradiated uranium are extremely small and are generally referred to in the art as "tracer quantities."

As used herein, the terms "tracer" and "tracer quantity" or their equivalents are employed as definitive of extremely small amounts of radioactive materials. For example, radioactive materials in concentrations of 10^{-10} to 10^{-14} molar are considered to be tracer quantities. Such extremely small amounts are incapable of identification by ordinary micro analytical methods, and are, therefore, generally identified by the radiations emitted therefrom by means of any of the usual counting mechanisms known to the art.

As illustrative of a typical neutron irradiated mass containing fission products the following tables are given:

TABLE A

Distribution of beta activity in neutron irradiated uranium for each fission element as percentage of total

Element	Cooling Time		
	30 Days	60 Days	100 Days
Ce.....	15	20	27
Sr.....	18	24	28
Y.....	17	22	23
Zr.....	6.8	9.6	12
Ru.....	2.6	3.4	3.5
Cb.....	1.3	2.2	3.4
Pr.....	8.0	3.9	0.72
Cs.....	0.15	0.33	0.72
La.....	13	5.5	0.72
Te.....	0.87	0.86	0.67
Ba.....	9.5	4.0	0.52

TABLE B

Distribution of effective gamma activity in neutron irradiated uranium for each fission element as percentage of total

Element	Cooling Time		
	30 Days	60 Days	100 Days
Ob.....	14	30	40
Zr.....	18	25	26
Ce.....	4.4	6.6	10
Ru.....	7.5	9.0	8.6
Sr.....	6.3	6.9	4.8
La.....	38	16	2.3
Y.....	1.8	2.4	2.3
Te.....	.85	0.70	0.79
Cs.....	.15	0.30	0.55
Ba.....	4.1	1.8	0.24
Pr.....	1.9	0.4	-----
L.....	1.1	0.15	-----

As illustrative of the method of obtaining the data for the above tables, the following is given. A mixed fis-

sion product solution is subjected to counting and is found to have a total beta activity of 453,000 counts/minute/milliliter. To a 1.00 ml. sample is added 20.0 mg. of Ru and by appropriate chemical manipulation the Ru is isolated and purified. The final precipitate of metallic Ru weighs 18.0 mg. and gives 4950 counts/minute. The chemical yield is therefore 90% and the count, corrected for chemical yield, is 5500 counts/minute or 1.21% of the total activity.

From the above tables it can be seen that certain fission products are listed as both beta emitters and gamma emitters. This situation results from the presence in neutron irradiated uranium of various isotopes of the elements which comprise the fission products. Thus, one isotope of an element may be a beta emitter while another isotope may be a gamma emitter. Furthermore, and as is more generally the case, certain of the isotopes may emit both types of radiation.

Some members of both the light and heavy groups of fission products may be readily separated from the neutron irradiated uranium mass in that they have been found to have chemical properties similar to the rare earths and can, therefore, be isolated by precipitation under carefully controlled conditions with about one hundred times their weight of carriers such as lanthanum fluoride, bismuth phosphate, and the like. However, many of the fission products in both groups do not respond to such treatment and considerable difficulty has been experienced not only in attempting to separate plutonium values from these fission products, but also in attempting to isolate certain of the fission product values in carrier-free radioactive form.

It can be seen from the above discussion that the separation and isolation of the various products formed as a result of the neutron irradiation of uranium is an extremely difficult task, particularly in view of the fact that extremely small quantities of the individual fission products are present in the materials under treatment. The problem is further complicated by the presence of the various isotopes and the fact that the elements, considered to be formed at the time of fission, may actually represent conversion products from certain of the fission product which have undergone extremely rapid change; that is, those fission products having extremely short half lives. In this connection, approximately 155 isotopes of the fission products involved have been identified and about 30% of these have half lives of over eight hours. Fission products have been identified that have half lives ranging from about 3 seconds to 10^4 years.

Since, as pointed out above, the fission product values contained in a solution of neutron irradiated uranium even after a considerable period of storage exhibit radioactive properties, it is particularly advantageous not only to separate these fission product values from plutonium values, but it is also advantageous in certain instances to isolate certain of the fission product values in carrier-free radioactive form in that they serve as an excellent source of radioactivity which may be utilized in various fields such as medicine and metallurgy.

I have found that selected components of a solution may be separated and recovered by a process which involves passing the solution through an adsorbent under conditions favoring the adsorption of the selected components and selectively eluting said components from the adsorbent.

It is accordingly an object of my invention to provide a process of separating selected components of a solution by adsorption and selective elution.

It is a further object of my invention to provide a simple process of separating radioactive components of a solution which process is capable of remote control.

It is still another object of my invention to provide a simple remotely controllable process of separating radioactive components of a solution which process may be

utilized in conjunction with other methods of separating the components of radioactive solutions.

These and other objects of my invention will become apparent to those skilled in the art upon becoming familiar with the following description when taken in conjunction with the accompanying drawing which diagrammatically illustrates a system which may be utilized in the practice of my invention.

Referring to the drawing, 1 designates a column containing a suitable adsorbent 2. Above column 1 is located tank 3 which is connected to column 1 by line 4 controlled by valve 6. To the upper portion of tank 3 are connected line 5 controlled by valve 6', line 7 controlled by valve 8 line 9 controlled by valve 10 and line 11 controlled by valve 12.

Passage from the bottom of column 1 is provided by line 13 which connects to line 14 controlled by valve 15 and line 16 controlled by valve 17.

In operation of the system described above, a solution containing the components to be separated is passed through line 5 into tank 3 wherein the condition of the solution is adjusted to favor adsorption of the selected components by adsorbent 2 in column 1. This condition is attained by the admission of suitable reagents through any one of lines 7, 9 or 11. When the desired condition has been reached, valve 6 in line 4 is opened and the solution is allowed to flow through column 1 and the desired components are removed by adsorbent 2, the remaining solution passing through lines 13 and 14 to disposal, valve 17 in line 16 being closed.

Following the adsorption of the selected components in the manner described above, these components are selectively eluted by means of the admission of various reagents into tank 3 through any one of lines 7, 9 and 11 and passage of the conditioned reagents through line 4 into and through column 1 containing adsorbed material on adsorbent 2. With valve 15 in line 14 closed, the eluate is passed through line 16, valve 17 being open, to storage or to any desired destination.

The solutions which may be processed in accordance with my invention are subject to wide variation. However, the invention is particularly adaptable to the separation of fission products contained in a solution of neutron irradiated uranium. The solution under process may contain uranyl nitrate hexahydrate together with fission products. When such a solution is treated, it is generally the practice to remove UO_2^{++} by means of dilute sulfuric acid or other sources of $SO_4^{=}$. In such a process, the UO_2^{++} is eluted before passage of any eluting agent selective for any fission products through the column.

Another solution which may be treated in accordance with my invention is that resulting from the ether extraction of uranyl nitrate hexahydrate solution. In the ether extraction process, UO_2^{++} is extracted from the solution containing the uranyl nitrate hexahydrate by means of ether and the residue is then contacted with water to obtain a water solution of fission products; such a water solution may also be processed for the recovery of individual fission products or of groups of fission products in accordance with my invention.

Generally speaking, a wide variety of adsorbents may be utilized in column 1 for the selective adsorption of components of the solution under treatment. When dealing with the separation of fission products from a solution of neutron irradiated uranium, particularly advantageous results have been obtained by the use of ion exchange adsorbents, in which the cation of the adsorbent is exchanged for a similarly charged ion of the substance to be adsorbed. It has been found that the process is particularly effective where the adsorbent used is a relatively inert organic material containing free sulphonic acid groups. Thus, the adsorbent may comprise phenol-formaldehyde resins, lignite, phenol-tannic acid resins, or the like, which contain numerous

$R-SO_3-R'$ groups in which R is an organic group such as a methylene group and in which R' is hydrogen or a metal ion, although R' is preferably H^+ or Na^+ . A particularly satisfactory adsorbent which may be employed is a phenol-formaldehyde condensation product containing methylene sulphonic acid groups ($-CH_2SO_3H$). In the adsorption process, the hydrogen of the sulphonic acid group is replaced by a cation of the substance to be adsorbed which thereupon forms a more or less loosely associated molecule with the residue.

As an example of a method by which a sulphonated resin may be prepared, 175 parts of 1-hydroxy-benzene-4-sulphonic acid are heated together with 40 parts of a formaldehyde solution of 30% strength for one-half hour to about 105° C. Then, further, 60 parts of formaldehyde are added and the temperature is kept for about 10 hours at 90° C. A hard black resin is formed which is stable to water and of conchoidal fracture. This resin is washed with water and ground to a powder. By regeneration with an acid or a solution of common salt, this base-exchanging body regains its original adsorption capacity.

Generally speaking, the eluting agents utilized in the practice of my invention may be varied, depending, among other things, upon the particular component to be eluted, and the conditions of elution. However, generally speaking, particularly advantageous results may be obtained by employing polycarboxylic acids and salts thereof as eluting agents. Examples of such eluting agents are oxalic acid, citric acid, tartaric acid, sodium citrate, sodium tartrate, potassium citrate, potassium tartrate, ammonium citrate, and ammonium tartrate. Particularly advantageous results are obtained by employing ammonium salts of polycarboxylic acids such as ammonium citrate and ammonium tartrate in that the positive ion NH_4^+ can be conveniently destroyed such as by aqua regia.

In one embodiment of my invention, a solution containing the components to be separated and recovered, such as a solution containing fission products resulting from neutron irradiated uranium is passed through column 1 containing an adsorbent such as an ion exchange resin having a plurality of $-CH_2SO_3H$ groups and the fission products adsorbed are selectively eluted by successive washes of the resin bed with different eluting agents. Certain groups of fission products or certain individual fission products are eluted by certain of the eluting agents and thereby recovered and the remaining groups of fission products or individual fission products are eluted by other eluting agents.

This embodiment of my invention is illustrated by the following specific examples.

EXAMPLE I

200 cc. of a mixture of fission products was prepared by admixing solutions of tracer in accordance with the following table:

TABLE C

	Tracer	No. cc	Total counts per second
65	Zr and Cr	40	41,600
	Ce	40	44,800
	Y	40	52,800
	Ba	40	19,600
	Sr	40	45,600

This synthetic mixture of fission products was then passed through a 100 cc. adsorption column containing an ion exchange resin characterized by having a plurality of $-CH_2SO_3H$ groups. Following adsorption of the fission product activities, the column was then washed with 100 cc. of water. Thereafter the adsorbent bed was

washed with 150 cc. of 1% oxalic acid. The eluate was collected and analyzed and found to contain 94% of the Cb and Zr activity originally present. The adsorbent bed was then washed with 100 cc. of water and thereafter 825 cc. of 5% tartaric acid containing 1/4 equivalent of NH₄OH was passed through the columns. The eluate was collected and analyzed and found to contain 96% of the Ce and Y activity originally present. 100 cc. of water was then passed through the adsorbent bed and thereafter the adsorbent was washed with 235 cc. of 3 N HCl. The eluate was collected and analyzed and found to contain 96% of the Ba and Sr activity originally present.

In accordance with another embodiment of my invention a solution containing the components to be separated and recovered, such as a solution containing fission products resulting from the neutron irradiation of uranium, is passed through a column containing a suitable adsorbent such as an ion exchange resin having a plurality of —CH₂SO₃H groups, and the adsorbed fission products are selectively eluted by washing the adsorbent bed with the same eluting agent employed at varying pH's. Certain of the fission products are eluted at a particular pH whereas the other fission products are eluted by the same eluting agent at a different pH.

This embodiment of my invention is illustrated by the following specific example:

EXAMPLE II

A solution containing Y and Ce activity was passed through a column containing a 0.65 cm.² x 60 cm. bed of a 40 to 60 mesh ion exchange resin characterized by having a plurality of —CH₂SO₃H groups resulting in the adsorption of the activities by the resin. 8 column volumes of a 4.75% solution of ammonium tartrate at a pH of 2.9 were passed through the column. The eluate was collected and identified as containing Y as 94% of the activity present. About 15 column volumes of ammonium tartrate solution at a pH of 2.8 was passed through the column. The eluate was collected and identified as containing Ce as 95% of the activity present.

The embodiments of my invention outlined above may be combined to obtain a more efficient separation of the components of a solution, if such a separation is desired. For example, certain of the components of a solution may be separated by utilizing a different eluting agent and the remaining components may be separated by utilizing the same eluting agent at different pH's.

This modification of my invention is illustrated by the following specific examples:

EXAMPLE III

200 ml. of a fission product mixture obtained by the ether and water extraction of a nitric acid solution of an 80 day old 1 kg. neutron irradiated uranium slug was passed through a 100 ml. column containing a 100 cm. x 1 cm.² bed of a 40-60 mesh ion exchange resin containing a plurality of —CH₂SO₃H groups at a rate of about 1 to 5 ml. per minute. The ion exchange resin containing adsorbed activity was then washed with about 300 ml. of water and thereafter washed with about 200 ml. of 0.25 N H₂SO₄ to insure removal of any uranium values present. The adsorbent bed was then washed with about 700 ml. of water and thereafter with 200 ml. of 1/2% oxalic acid. The eluate was collected and analyzed and found to comprise approximately 99.4% Zr and Cb activity, the ratio of Zr to Cb being approximately 3 to 1. Following the removal of the abovementioned activities, 800 ml. of 4.75% ammonium citrate at a pH of 2.9 was passed through the column over a period of approximately 8 hours. A cut was taken between the sixth and seventh hour of elution and analyzed and the Y activity was found to be 98.9% of the total activity present. A second cut was taken between approximately the seventh and eighth hour of elution and analyzed and found to contain Y as 71.8% of the total activity present.

Following elution of the activities as indicated above, approximately 600 ml. of a 4.75% ammonium citrate solution at a pH of 3.3 was passed through the column over a period of about 5 hours. A cut was taken between the second and third hour of elution and analyzed and found to contain more than 90% of the activity present in the form of Ce activity.

EXAMPLE IV

- 10 A 200 ml. solution of fission products obtained by the ether and water extraction of a nitric acid solution of a 40 day old 1 kg. neutron irradiated uranium slug was passed through a 100 ml. resin column containing a 100 cm. x 1 cm.² bed of a 40-60 mesh ion exchange resin characterized by having a plurality of —CH₂SO₃H groups at a rate of approximately 1-2 ml. per minute. The adsorbed material was then washed with about 300 ml. of 0.5 N H₂SO₄ to remove any uranium values which may have been present. About 250 ml. of 0.5% oxalic acid were passed through the column and the eluate was collected. Analysis of this eluate indicated that all of the activity present therein was attributable to Zr and Cb. The adsorbent bed was then washed with 535 ml. of a 5% ammonium tartrate solution at a pH of 2.7. The last 25 100 ml. of eluate to flow from the column was collected and analyzed. This cut was found to contain Y in the amount of 95% of the activity present. The column was then washed with about 500 ml. of 5% ammonium tartrate solution at a pH of 2.9. Approximately the second 30 200 ml. of eluate from the column was collected and divided into a 120 ml. cut which was analyzed and found to contain Ce as approximately 75% of the total activity present and a 60 ml. cut which was analyzed and found to contain Ce as approximately 94% of the total activity present. The final 63 ml. of eluate from the column was analyzed and found to contain Ce as 99% of the activity present. The column was then washed with a 5% ammonium tartrate solution at a pH of 3.1, the eluate was analyzed and the first 260 ml. thereof was 35 found to contain Ce as 99% of the total activity present. Thereafter a 5% solution of ammonium citrate at a pH of 5.0 was passed through the column and after a 185 ml. of effluent had come off the column the next 45 ml. upon analysis showed Sr as 99% of the activity present. 40 The next following 108 ml. of eluate upon analysis showed Sr at 94% of the activity present. After the passage of about 350 ml. of eluting agent through the column, the eluate upon analysis showed Ba as 99% of activity present.

EXAMPLE V

- 45 A 520 ml. solution of mixed fission products obtained by the ether and water extraction of a nitric acid solution of a 30 day old 1 kg. neutron irradiated uranium slug was passed through a 100 ml. resin column containing a 100 cm. x 1 cm.² bed of 40-60 mesh ion exchange resin characterized by having a plurality of —CH₂SO₃H groups. The adsorbed material was washed with 410 ml. of 0.5 N H₂SO₄ to remove any uranium values which may have been present. The adsorbed material was then washed with about 160 ml. of 1/2% oxalic acid, the next 60 ml. of eluate was analyzed and found to contain Zr and Cb as 99.9% of the activity present, the bulk of which was in the form of Zr. Thereafter the adsorbed material was washed with about 300 cc. of 7% oxalic acid solution and the eluate analyzed and found to contain approximately 85% of the activity in the form of Cb with the preponderant portion of the remaining activity being in the form of Zr.

- 65 The resin bed was then washed with about 1600 ml. of 5% ammonium citrate solution at a pH of 2.75. The first 800 ml. of effluent showed little activity but the next 400 ml. of effluent upon analysis indicated that Y constituted approximately 98.3% of the activity. The next 265 ml. of effluent upon analysis indicated Y as 70 approximately 97.8% of the activity. Following the pas-

sage of the above-mentioned 1600 ml. of eluting agent approximately 950 ml. of 5% ammonium citrate at a pH of 3.35 was passed through the column. After approximately the first 200 ml. of effluent had passed from the column, the next 350 ml. of effluent upon analysis indicated that Ce constituted approximately 97.7% of the total activity present. The next 250 ml. of effluent upon analysis indicated the activity present to be comprised of approximately 86% Ce.

The resin bed was then washed with approximately 600 ml. of 5% ammonium citrate at a pH of 4.76. The first 380 ml. of effluent from the column upon analysis indicated that Sr constituted approximately 90% of the total activity present. The last 220 ml. of effluent upon analysis indicated that Ba constituted approximately 90% of the total activity present.

In still another embodiment of my invention separation of components of a solution may be made by differential rates of elution from an adsorbent bed. For instance, in case of barium and strontium it has been found that barium may be eluted more rapidly than strontium at the same pH. This pH is one of which barium is eluted in higher percentage than strontium. The two can be separated completely therefore if a long column and a large volume of eluting agent are employed. It is also possible to utilize a short column and a small volume of eluting agent to give a degree of separation which would be practically complete if repeated frequently enough. The separation of components by differential rate of elution is illustrated in the specific example V in the last step where barium and strontium are separated by differential rate of elution. The following example is also illustrative of this embodiment of my invention.

EXAMPLE VI

125 cubic cm. of an ion exchange resin containing a plurality of $-\text{CH}_2\text{SO}_3\text{H}$ groups was suspended in distilled water and transferred to an upright glass tube 1 cm. in diameter and allowed to settle. A stopcock was inserted in the bottom of the glass tube by means of a rubber stopper covered with stainless steel gauze to allow liquid to pass through the column at the desired rate and to keep the resin from passing out. About 500 ml. of 6 N HCl was then passed through the column to convert the resin to its acid form. The column was washed with distilled water until liquid leaving the column had the same pH as the water entering the column. A solution of a mixture containing Pr, Nd, Il, and a trace of Y activity was passed through the column at a rate of 1 to 2 ml. per minute. The column was then washed with about 100 to 200 ml. of distilled water. The column was then washed with a 5% ammonium citrate solution at a pH of 2.75 which was prepared by dissolving 50 g. of citric acid in 100 ml. of distilled water and adding enough concentrated NH_4OH to effect the desired pH. The eluting agent was passed through the column at the rate of about 1 ml. per minute. The first portion of the effluent from the column was analyzed and found to contain approximately 90% of the original Il present. The second portion of the effluent was analyzed and found to contain approximately 90% of the Nd present. The third portion of the effluent was analyzed and found to contain approximately 90% of the Pr activity originally present.

It is also possible within the scope of my invention, as illustrated by Example V, to utilize all of the above-mentioned methods of selective elution in the separation of the components of a solution.

Another method of selective elution which may be employed in the practice of my invention is that involving varying the concentration of eluting agent while maintaining a uniform pH.

Generally speaking, the invention is particularly adaptable to the separation of metal cations especially those cations which occur as fission products in the preparation of radioactivities either with or without added inactive

carriers. The process of the invention is equally effective for the separation of mixtures of, or individual fission products. Generally speaking, the preferred pH for the initial and eluting solution will depend on the acid used, on the adsorbent used and on the cations to be adsorbed; ordinarily the adsorption solution will have a lower pH than the eluting solution, for instance 1-3 for adsorption as compared to 3 to 6 for elution.

In the practice of my invention, it is particularly advantageous to remove any excess acid such as tartaric or citric acid which may be adsorbed, particularly where tracer quantities are involved. Such a removal may be accomplished by washing the adsorbent with distilled water which procedure removes the excess acid without removing the desired cations.

When ammonium ion is present in the eluting agent or complexing agent, the adsorbate in the column is generally contaminated therewith. Should removal of NH_4^+ be desired, it may be accomplished by washing the adsorbate with 3-6 N HCl. Such a procedure also removes other inactive cations such as iron, aluminum and the like which may be present in the final adsorbate.

An alternate procedure for removal of NH_4^+ is to remove the cations from the body of adsorbent with 3-6 N HCl and thereafter destroy the NH_4^+ by the addition of aqua regia to the eluate.

The desired activity may be separated from the eluting agent by evaporating the eluate liquid to dryness thus isolating the activity as the salt of the acid employed in the eluting agent.

While the invention has been particularly described with reference to the separation of the components of a solution of neutron irradiated uranium, it is to be understood that other types of solutions may be separated by means of the process of the invention. For example, the invention may be applied to the separation of rare earths as well as to the separation of N_{233} from neutron irradiated thorium. The invention may also be applied to the separation of cyclotron bombarded materials.

While the above description makes particular mention of the separation of cations, the process of the invention may also be utilized in the separation of anions. One method of separating anions is that involving the utilization of an adsorbent selective for anions such as an anion exchange resin. In some instances, the anions of the desired components may be converted to cations and processed in a manner similar to that above described.

In the specification and claims the following terms have the following meanings.

The term "effluent" or its equivalent is intended to include any material coming off of the columns.

The term "eluate" or its equivalent is intended to include any effluent bearing a desired product from a column.

The term "eluting agent" or its equivalent is intended to include a material which removes activity from a column.

The term "adsorption" is utilized in referring to removal of components from the solution. It is to be understood, however, that the invention is not to be limited in any sense by the theory upon which the process is based and that this term is used as it is generally employed in the art of chromatographic separation.

While the invention has been described with reference to certain particular embodiments and with reference to certain specific examples, it is to be understood that the invention is not to be limited thereby. Therefore, changes, omissions, and/or additions may be made without departing from the spirit of the invention as defined in the appended claims which are intended to be limited only as required by the prior art.

I claim:

1. A process of separating the components of a mixture of fission product metal cations containing zirconium, columbium, cerium, yttrium, barium, and strontium

cations, which comprises passing a solution of said cations through a granulated mass of an ion exchange resin characterized by having a plurality of $-\text{CH}_2\text{SO}_3\text{H}$ groups, eluting said zirconium and columbium by means of oxalic acid, eluting said cerium and yttrium by means of tartaric acid, and eluting said barium and strontium by means of hydrochloric acid.

2. A process of separating yttrium and cerium cations from a solution containing the same which comprises passing said solution through a granulated mass of ion exchange resin characterized by having a plurality of $-\text{CH}_2\text{SO}_3\text{H}$ groups, passing a solution of ammonium tartrate at a pH of approximately 2.9 through said resin, thereby eluting said yttrium, and thereafter passing a solution of ammonium tartrate at a pH of approximately 2.8 through said resin, thereby eluting said cerium.

3. A process of separating the components of a mixture of fission product metal cations containing zirconium, columbium, cerium and yttrium cations which comprises passing a solution of said mixture through a granulated mass of an ion exchange resin characterized by having a plurality of $-\text{CH}_2\text{SO}_3\text{H}$ groups, passing a dilute solution of oxalic acid through said resin thereby eluting said zirconium and columbium, passing a dilute solution of ammonium tartrate at a pH of approximately 2.9 through said resin thereby eluting a preponderant portion of said yttrium, and passing said dilute solution of ammonium citrate at a pH of approximately 3.3 through said resin thereby eluting the preponderant portion of said cerium.

4. A process of separating the components of a mixture of fission product metal cations containing zirconium, columbium, yttrium, cerium, barium and strontium cations which comprises passing a solution of said mixture at a pH less than 3 through a body of granulated ion exchange resin characterized by having a plurality of $-\text{CH}_2\text{SO}_3\text{H}$ groups, washing said resin containing adsorbed fission products with a dilute oxalic acid solution thereby eluting the preponderant portion of said zirconium and columbium, thereafter washing said resin containing adsorbed material with a dilute ammonium tartrate solution at a pH of approximately 2.7 thereby eluting the preponderant portion of said yttrium, washing said resin containing adsorbed material with a further quantity of said ammonium tartrate solution at a pH of approximately 2.9, thereby eluting the preponderant portion of said cerium, and thereafter washing said resin containing adsorbed material with a further quantity of said ammonium tartrate solution at a pH of approximately 5.0, thereby initially eluting from said resin said strontium and finally eluting from said resin said barium.

5. In a process of separating radioactive fission product metal cations including yttrium cations from a solution containing the same which comprises adsorbing said fission product cations upon an ion exchange resin characterized by having a plurality of $-\text{CH}_2\text{SO}_3\text{H}$ groups and selectively eluting said fission products from said resin; the step comprising passing through said resin containing adsorbed fission products an aqueous solution containing up to 5% by weight of a compound selected from the group consisting of ammonium tartrate and ammonium citrate adjusted to a pH between about 2.7 and 2.9 thereby selectively eluting said yttrium.

6. In a process of separating radioactive fission product metal cations including cerium cations from a solution containing the same which comprises adsorbing said fission product cations upon an ion exchange resin characterized by having a plurality of $-\text{CH}_2\text{SO}_3\text{H}$ groups and selectively eluting said fission products from said resin; the step comprising passing through said resin containing adsorbed fission products a dilute aqueous solution of a compound selected from the group consisting of ammonium tartrate and ammonium citrate adjusted to a pH of approximately 2.9 to 3.3 thereby selectively eluting said cerium.

7. In a process of separating radioactive fission prod-

uct metal cations including barium cations from a solution containing the same which comprises adsorbing said fission product cations upon an ion exchange resin characterized by having a plurality of $-\text{CH}_2\text{SO}_3\text{H}$ groups and selectively eluting said fission products from said resin; the step comprising passing through said resin containing adsorbed fission products a dilute aqueous solution of a compound selected from the group consisting of ammonium citrate and ammonium tartrate adjusted to a pH of about 5 thereby selectively eluting said barium.

8. A process for the separation of fission-product metal cations from an aqueous solution containing the same, which comprises contacting said solution with a comminuted mass of ion-exchange adsorbent to thereby effect adsorption of said fission-product cations thereupon, and thereupon contacting the resulting fission-product-bearing adsorbent with a dilute aqueous solution of a salt of a polycarboxylic acid, to thereby elute said fission products from the adsorbent therewith.

9. The process of claim 8 wherein said salt of a polycarboxylic acid is chosen from the group consisting of ammonium, sodium, and potassium salts thereof.

10. The process of claim 8 wherein said salt of a polycarboxylic acid is an ammonium polycarboxylate.

11. The process of claim 8 wherein said salt of a polycarboxylic acid is ammonium tartrate.

12. The process of claim 8 wherein said salt of a polycarboxylic acid is ammonium citrate.

13. The process of claim 8 wherein said ion-exchange adsorbent is an ion-exchange adsorbent resin having a plurality of $-\text{CH}_2\text{SO}_3\text{H}$ groups.

14. The process of claim 8 wherein said aqueous solution of a salt of a polycarboxylic acid is an approximately 5% by weight solution of an ammonium polycarboxylate.

15. The process of claim 8 wherein said aqueous solution of a salt of a polycarboxylic acid is a solution, having a pH within the approximate range of pH 2.7 to 6, of an ammonium polycarboxylate.

16. A process for the separation of rare earth metal cations from an aqueous solution containing the same, which comprises contacting said solution with a comminuted mass of an ion-exchange adsorbent, to thereby effect adsorption of said rare earth cations thereupon, and thereafter passing through the resulting rare-earth bearing mass of adsorbent an aqueous solution of a salt of a polycarboxylic acid chosen from the group consisting of ammonium, sodium, and potassium salts thereof, to thereby elute said rare earth from the adsorbent mass therewith.

17. A process for selectively separating constituent species of fission-product metal cations from an aqueous solution containing the same, which comprises passing said solution through a body of comminuted ion-exchange adsorbent resin to thereby effect adsorption of said fission-product cations thereupon, and thereafter passing through the resulting fission-product-bearing adsorbent body a succession of different eluants, at least one of which comprises an aqueous solution of a salt of a polycarboxylic acid chosen from the group consisting of ammonium, sodium, and potassium salts thereof, to thereby effect selective elution from the adsorbent of fission-product species therewith.

18. A process for selectively separating constituent species of fission-product metal cations from an aqueous solution contacting the same, which comprises passing said solution in a substantially unidirectional flow through a bed of comminuted ion-exchange adsorbent resin to thereby effect adsorption of fission-product cations thereupon, thereafter passing through the resulting fission-product-bearing adsorbent bed, in substantially the same direction as the flow of solution during adsorption, an aqueous solution of a salt of a polycarboxylic acid chosen from the group consisting of ammonium, sodium, and potassium salts thereof, to thereby elute different fission-product species at differential rates through said bed,

and collecting successive fractions of the resulting eluate, each rich in a respective fission-product species.

19. A process for selectively separating constituent species of fission-product metal cations from an aqueous solution containing the same, which comprises passing said solution through a body of comminuted ion-exchange adsorbent resin, to thereby effect adsorption of fission-product cations thereupon, and thereafter passing through the resulting fission-product-bearing body of adsorbent an aqueous solution of a salt of a polycarboxylic acid chosen from the group consisting of ammonium, sodium, and potassium salts thereof, while progressively increasing the pH thereof, to thereby selectively elute particular fission-product species with different pH's of said salt solution.

20. A process for selectively separating constituent species of fission-product metal cations from an aqueous solution containing the same, which comprises passing said solution through a body of comminuted ion-exchange adsorbent resin, to thereby effect adsorption of fission-product cations thereupon, and thereafter passing through the resulting fission-product-bearing body of adsorbent an aqueous solution of a salt of a polycarboxylic acid chosen from the group consisting of ammonium, sodium, and potassium salts thereof, while progressively increasing the polycarboxylate concentration thereof, to thereby selectively elute particular fission-product species with different polycarboxylate concentrations of said salt solution.

21. A process for selectively separating different rare earth metal cations from an aqueous solution containing a plurality of the same, which comprises passing said

solution, in a substantially unidirectional flow, through a bed of comminuted ion-exchange adsorbent resin, to thereby effect adsorption of said rare earth cations thereupon, thereafter passing through the resulting rare-earth-bearing adsorbent bed, in substantially the same direction as the flow of solution during adsorption, an aqueous solution having a pH within the approximate range of pH 2.7 to 6, of a salt of a polycarboxylic acid chosen from the group consisting of the ammonium, sodium, and potassium salts thereof, to thereby elute the different adsorbed rare earth species at differential rates through said adsorbent bed, and thereafter collecting successive fraction of the resulting eluate each rich in respective rare earth species.

15. 22. The process of claim 21 wherein said aqueous solution of a salt of a polycarboxylic acid is a solution having a pH of approximately 3, of an approximately 5 percent by weight concentration of ammonium citrate.

20 23. The process of claim 21 wherein said aqueous solution of a salt of a polycarboxylic acid is a solution, having a pH of approximately 3, of an approximately 5 percent by weight concentration of ammonium tartrate.

UNITED STATES PATENT OFFICE
CERTIFICATE OF CORRECTION

Patent No. 2,877,094

March 10, 1959

Joseph X. Khym

It is hereby certified that error appears in the printed specification of the above numbered patent requiring correction and that the said Letters Patent should read as corrected below.

Column 4, line 2, for the numeral "453,000" read -- 453,600 --; line 16, after "gamma" for "eitter" read -- emitter --; column 8, line 46, after "Sr" for "at" read -- as --; column 9, line 51, for "distiled" read -- distilled --; column 10, line 37, for "N₂₃₃" read -- U₂₃₃ --; column 1, line 65, for "contacting" read -- containing --.

Signed and sealed this 25th day of August 1959.
